DEVICE FOR TRIMMING PAPER AND THE
LIKE

Harry L. Sahl, Boston, Mass.

Application August 21, 1936, Serial No. 97,182

4 Claims. (Cl. 164—83)

This invention relates to improvements in cutting tools and particularly to a device for trimming wall paper and the like.

The object of the invention is to provide a simple, effective device for trimming the edge of wall paper and other forms of thin sheet material usually cut or trimmed with a knife.

Another object of the invention is to provide a device utilizing thin flat safety razor blades of the various types easily obtainable, and which may be easily and quickly inserted therein and removed therefrom as required.

Another object of the invention is to provide an antifriction member, preferably a grooved roller having narrow peripheral portions, as a means for smoothing out certain types of sheet material in advance of the blade, for aiding in guiding the device during the cutting operation, and for preventing the holder from contacting with the material to be cut and in the case of wall paper preventing the paste from squeezing from said paper at the edges thereof during the cutting operation.

The invention consists in a device for trimming and cutting wall paper and like sheet material as set forth in the following specification and particularly as pointed out in the claims thereof.

Referring to the drawings:

Fig. 1 represents a front elevation of a cutting tool embodying my invention and having a double edge type safety razor blade embodied therein.

Fig. 2 is an end elevation of the device.

Fig. 3 is a perspective view of a clamping plate for a double edge type razor blade.

Fig. 4 is a front elevation of a portion of a holder embodying my invention, but illustrating a single edge type safety razor blade mounted thereon.

Fig. 5 is an end elevation of the device illustrated in Fig. 4 viewed from the left of said figure.

Fig. 6 is a detail view illustrating an alternate method of mounting the grooved roller upon the holder.

Like numerals refer to like parts throughout the several views of the drawing.

In the drawing, referring particularly to Figs. 1, 2 and 3, 7 represents a holder, preferably constructed of wood and provided with a handle 8. A front face 9 of the holder 7 is flat, and in the operation of the device is adapted to engage a straight edge of well-known type utilized by paper hangers and constituting a guide for the device. The front face 9 is provided with a shallow recess 10 for receiving a backing plate 11, a safety razor blade 12 and a clamping plate 13, the front or

outer face of said clamping plate aligning with the front face 9 of the holder 7 and in effect constituting a continuation thereof. The clamping plate 13 has two pins 14 rigidly secured thereto and projecting rearwardly therefrom, and said pins pass through a slot 15 provided in the blade 12, through holes 16 provided in the backing plate 11, and through holes 17 provided in the holder 7, and said clamping plate, blade and backing plate are all securely clamped to said holder by means of thumb nuts 18 which have screw-threaded engagement with the pins at the rear of the holder. In the form of the device illustrated in Fig. 1 a double edge type safety razor blade is utilized and approximately one-half of one cutting edge of said blade protrudes from between the clamping plate 13 and backing plate 11, and is available for cutting purposes at one time. It is evident, however, that as the cutting edge of the blade becomes dulled, said blade may be repositioned upon the holder to permit the remaining portions of both cutting edges of the blade to be utilized until it is finally necessary to replace the blade.

In performing the cutting operation the device is pulled across the surface of the sheet material represented at A in the direction of the arrow a, Fig. 1, it being understood that said material rests upon a table or other suitable form of support not illustrated in the drawing. Mounted upon the holder 7 in advance of the cutting blade 12 is a bracket 19 upon which a grooved guide roller 20 is rotatably mounted. The bracket 19 is rigidly secured to the under edge of the holder 7 by means of a screw-threaded spur 21 or any other desired means. The roller 20 is provided for the purpose of engaging the sheet material A in advance of the cutting blade 12, thereby preventing any portion of the under edge of the holder 7 from rubbing over the surface of the sheet material. The roller 20, furthermore, in the case of certain types of sheet material, will smooth out wrinkles and uneven places in said materials as the roller passes thereover, thereby increasing the effectiveness of the device. In the case of wall paper, where the paste is applied to the rear surface of the paper and the latter is folded upon itself before it is trimmed, it is important that the paste shall not be squeezed from between the layers of paper during the operation of trimming the margin therefrom. The grooved roller 20, therefore, is provided with narrow peripheral portions 22 which engage correspondingly narrow portions of the paper and do not cause any paste to be

forced outwardly beyond the edges of the paper. Finally, the roller 20 acts to guide and steady the device as it is moved across the sheet material during the cutting operation, thereby making 5 it possible to obtain a clean, sharp, straight cut.

In the operation of the device, when a straight cut is desired, a straight edge, well known in the art, is utilized and the device is pulled across the surface of the material with the front faces 10 of the holder 7 and clamping plate 13 contacting with the surface of the straight edge. As the device is moved over the surface of the material sufficient pressure is applied to the device to force the cutting blade through said material and a 15 clean straight cut is produced.

In Figs. 4 and 5 of the drawing I have illustrated a modified embodiment of my invention in which a single edge type of safety razor blade 23, well known in the art, is mounted in the recess 10 of 20 the holder 7 between a backing plate 24 and a clamping plate 25. A pin 26 projects rearwardly from the clamping plate 25 through openings 27 and 28 provided in the blade 23 and backing plate 24 respectively, and through an opening 29 provided in the holder 7; and said clamping plate 25, blade 23 and backing plate 24 are all clamped securely to said holder by means of a thumb nut 30 which has screw-threaded engagement with the pin 26 at the rear of the holder. A short pin 31 projects rearwardly from the clamping plate 25 through a slot 32 provided at the end of the blade 23, through an opening provided in the backing plate 24 and into a hole 33 provided in the holder; and said pin 31 co-operates with the 35 pin 26 in positioning the blade 23 upon said holder. The position of the blade 23 may be changed end for end upon the holder 7 in order that the entire cutting edge of said blade may be utilized.

In cutting or trimming certain kinds of sheet 40 materials, where a curved cut is desired, it may be advantageous to provide the holder 7 with a grooved roller mounted upon a bracket that will swivel upon said holder. Referring, therefore, to Fig. 6, a bracket 34 is secured to a holder 7 45 by means of a screw 35 in a manner which will enable said bracket to rotate freely upon the holder, and a grooved roller 20 provided with narrow peripheral portions 22 is rotatably mounted upon said bracket. This structure will enable 50 the user of the device to effectively maintain

the guiding face of the device in contact with the curved edge of a pattern that may be utilized in obtaining the curved cut desired.

I claim:

1. A device for trimming wall paper and the like comprising a holder adapted to be grasped by the hand, means to clamp a cutting blade to a face of said holder, and a roller provided with relatively narrow spaced apart peripheral portions mounted upon the holder in advance of the cutting blade and adapted to contact with the material to be cut during the cutting operation, whereby said holder is prevented from contacting with said material. 5

2. A device for trimming wall paper and the like comprising a holder adapted to be grasped by the hand, and provided with a face adapted to engage a pattern during the cutting operation, said face having a recess therein for receiving a cutting blade, means to clamp said blade to said holder in said recess, and an anti-friction member mounted upon the holder and embodying therein relatively narrow spaced apart work engaging portions positioned in advance of said blade and co-operating therewith to prevent said holder from contacting with the material to be cut. 10

3. A device for trimming wall paper and the like comprising a holder adapted to be grasped by the hand, and provided with a face adapted to engage a pattern during the cutting operation, said face having a recess therein for receiving a cutting blade, means to clamp said blade to said holder in said recess, and a grooved roller provided with relatively narrow peripheral portions mounted upon said holder in advance of the cutting blade and adapted to contact with the material to be cut during the cutting operation, whereby said blade holder is prevented from contacting with said material. 15

4. A device for trimming wall paper and the like comprising a holder adapted to be grasped by the hand, means to clamp a cutting blade to a face of said holder, a bracket mounted to swivel upon said holder in advance of the cutting blade, and a grooved roller mounted upon said 40 bracket and adapted to contact with the material to be cut during the cutting operation, whereby said holder is prevented from contacting with said material. 45
